Patented Mar. 18, 1969

213,575

MEAT PLATTER

Irving Rubin, 800 Newton St., Chestnut
Hill, Mass. 02167

Filed Oct. 30, 1967, Ser. No. 9,211

Term of patent 14 years

U.S. Cl. D44—10
Int. Cl. D7—01

FIG. 1

FIG. 2

FIG. 1 is a perspective view of a meat platter showing my new design;

FIG. 2 is a top plan view;

FIG. 3 is a bottom plan view;

FIG. 4 is an end elevational view;

FIG. 5 is a side elevational view;

FIG. 6 is a section in elevation taken along the line

6-6 of FIG. 2; and

FIG. 7 is a section in elevation taken along the line 7-7 of FIG. 2.

I claim:

The ornamental design for a meat platter, substantially as shown.
